UNITED STATES PATENT OFFICE.

KATE A. BRADLEY, OF ATLANTIC CITY, NEW JERSEY.

GAME

1,228,090.

Specification of Letters Patent.

Patented May 29, 1917.

Application filed August 19, 1916. Serial No. 115,880.

To all whom it may concern:

Be it known that I, KATE A. BRADLEY, a subject of the King of Great Britain, residing at Atlantic City, in the county of 5 Atlantic and State of New Jersey, have invented new and useful Improvements in Games, of which the following is a specification.

The invention relates to games and toys 10 and more particularly to games such as are generally found at parks, carnivals, sea-shore resorts and the like, an object of the invention being to provide a game that will interest and amuse grown persons and children and in which there will be an element 15 of chance in obtaining certain results, requiring also keenness of the eye and accurate manipulation in throwing to insure success.

20 Among other features the invention comprehends balls which are thrown at a basket or net from a prescribed distance with the object of having the balls pass into the basket; those balls passing into the basket 25 counting as hits whereas the balls that are not accurately thrown and do not pass into the basket are regarded as misses and therefore not to be counted in obtaining accurate results.

30 To this end the game apparatus is constructed to return the counting balls into a position where the final result can be quickly determined, whereas the balls that miss the basket are returned in a different 35 manner and arrangement, all of the balls however being ultimately returnable into a box or onto a table adjacent to the player so that the player can repeat the throwing operation or a new player take his place, 40 the entire operation being simple and readily accomplished to make the game interesting and pleasing to the participants and on-lookers.

In the further disclosure of the invention 45 reference is to be had to the accompanying drawings, constituting a part of this specification, in which similar characters of reference denote corresponding parts in all the views, and in which,

50 Figure 1 is a vertical longitudinal sectional view taken through the game apparatus;

Fig. 2 is a fragmentary plan view of the structure shown in Fig. 1;

Fig. 3 is a front elevation of the basket and adjacent parts;

Fig. 4 is a vertical transverse sectional view taken on the line 4—4 in Fig. 1, looking in the direction of the arrow; and

Fig. 5 is a fragmentary enlarged vertical sectional view showing the operation of the ball elevating mechanism and the construction of the box table.

Referring more particularly to the views the numeral 10 indicates a floor or the ground and the numeral 11 a back wall, the 65 floor 10 having a depressed portion 12 at the front end, and at which point the operator or player will stand. An incline 13 extends from the front to the wall 11 as shown and a table 14 is situated at the front 70 end of the floor and adjacent the front end of the incline.

Secured in spaced relation to the wall 11 by suitable brackets 15, is a basket 16, formed of any desirable material and spaced 75 a distance from and above the rear end of the incline 13, a bracket 17 being also secured to the wall 11 to project outwardly above the basket and swingingly support an ornamental element 18 that may be conveniently fashioned to represent a face of amusing expression, the same in this instance being depicted with an electric bulb 18^a in an eye of the face, said bulb by means of wires 18^b being connected to a battery 18^c, 85 with another wire 18^d in connection with the battery, connected to a projection 18^e on the bracket 17, so that when the element 18 is struck by a ball and thereby oscillated, it will strike the projection 18^e and result 90 in illumination of the bulb 18^a. It will of course be understood that I merely describe and show diagrammatically one method of accomplishing this result, and it is obvious that deviations may be made in this construction.

The lower extremity of the basket 16 is provided with an ornamental element 19 of similar design as the element 18, with the exception that the mouth 20 of the element 100 19 is separately formed from the balance of the figure, and is connected with a swinging bottom 21 hinged to a permanent bracket 22, fixed to the wall 11. The bottom 21 is adapted to normally close the lower extremity of the basket 16, this being accom-

plished through the agency of a spring 23, however, when a ball or other missile 24 has been cast into the basket, the weight of said ball will be sufficient to overcome 5 the action of the spring 23, thus permitting the bottom 21 to oscillate to an open position, so as to discharge the ball from the basket. It will be apparent that when the bottom 21 opens, the element 19 will be 10 given the appearance of opening its mouth, so that the ball 24 will have the effect of rolling out of the mouth of the ornament 19, as will be readily understood. In certain instances, when the mouth opens, mechanism 15 may be provided for protruding a tongue out of the mouth, in order to add to the visual interest of the game.

Positioned below the swinging bottom 21 is a ball receiving chute or runway 25, the 20 latter being employed to receive the balls discharged from the basket 16 and to convey them to the table 14, conveniently disposed and within ready reach of the players of the game. The runway 25 is formed to 25 provide a relatively enlarged ball receiving extremity 26, disposed contiguously to the bottom 21, and terminating in an angularly disposed portion 28, extending over to a point adjacent to a side 27 of the game apparatus. The portion 26 is provided in order that the balls discharged thereby will be delivered to one side of the game, to relieve the same of the possibility of interfering with a player, while the latter is throwing 35 a ball toward the basket. The portion 26 terminates in an inclined extension 28, located adjacent to the side 27 and disposed substantially parallel to the incline 13, said extension ending in juxtaposition with respect to the table 14, so that balls delivered by the extension or runway will be capable of being readily collected by the players.

In playing the game, a player will stand at a position substantially near the end of 45 the incline 13 and will endeavor to throw one or more balls at the elements 16 and 18 with the view of dropping the balls into the basket 16. If successful in his attempt, each ball entering the basket is entitled to be 50 called a "hit," and the balls failing to enter the basket are called "misses," the greatest number of "hits" made by one of two or more players, permits the player making the majority of hits to win the game. The 55 game may be, also, played by a single player with equal facility and enjoyment.

Special mechanism has been provided for systematically collecting the thrown balls of the game, so that the balls will be directed 60 to the table 14 where they may be conveniently reached by the players. This mechanism, in its preferred embodiment, consists of the table 14 of peculiar construction, the same constituting frame bars 29, utilized for 65 the support of the table 14, a vertically mov-

able lift 30, and a sliding door 31, for controlling the action of balls conveyed by the extension 28 into the table 14.

The edge 32 of the incline 13 terminates in an inclined trough 33, inclined toward 70 the lift 30, so that the balls which fail to enter the basket 16, will be collected by the trough and subsequently deposited upon the lift 30. The balls which enter the basket 16 are, as has been previously related conducted by the runway 25 to a point near the table 14, but are normally prevented from entering the table by the door 31, until certain controlling mechanism has been operated. The lift 30 is connected for vertical 75 movement with the frame bar 27, and in order that the lift may be elevated to a place substantially equal to that of the table 14, said lift is provided, on one side, with a stud 34 which operates within a slot 35 formed on a vertical rocking lever 36. The lever 36 is pivoted, as at 37, to the table casing 38 and is formed with an offset handle portion 39, by means of which the lever may be rocked to elevate the lift. One side of 80 the casing 38 is open as at 40, so that when the lift 30 reaches the limit of upward movement the balls carried thereby will gravitate upon the table 14, the action being facilitated by the inclined bottom of the lift. 95

Coincident with the release of the balls from the lift 30 and the table 14, the balls located within the runway 25 are also permitted to escape, so as to be deposited upon the table 14. The operation is performed 100 by providing the lift with pin members 41, which when the lift is nearing its extreme elevated position, will contact with the lower edge of the door 31, so as to push the latter upwardly in union with the lift. This operation uncovers the lower extremity of the runway and permits the balls located therein to roll out upon the table 14. Guide brackets 42 are utilized to guide the door 31 in its roll of movement. It will be understood that when the game is used for commercial purposes, a coin recording device 105 may be associated with the lever 36, so that an exact record may be kept as to the number of times the game is played or operated. 110

From the foregoing it will be manifest that the objects of the present invention have been achieved and that all of the advantageous features of a game of this element, such as recreation, pleasure and exercise promoting qualities are, among others, present. The device is relatively simple in operation, can be conveniently operated and forms a distinct addition and improvement in the art to which it relates. While the preferred form of the inventor can be set forth in detail, it is, of course, understood that various structural changes may be made in the same without departing from the principles or scope of the invention. 115

Having described the invention, what is claimed as new and patentable is:

1. A game of the class described comprising a fixed ball-receiving receptacle, a ball deflecting element swingingly suspended above said receptacle, a ball receiving table and means located beneath said receptacle to receive balls discharged from said receptacle and to deliver the balls to said receiving 10 table.
2. A game of the class described comprising a ball-receiving receptacle, means for deflecting balls into said receptacle, a swinging bottom normally closing one end of said 15 receptacle and being adapted to open upon receiving the weight of the ball, and inclined runways for returning balls thrown toward said receptacle to a point within convenient reach of the players of the game.
3. A game of the class described, comprising a receptacle, movable means for deflecting balls into said receptacle, a swinging bottom carried by said receptacle, said bottom being capable of opening upon receiving 20 the weight of a ball to discharge the latter from said receptacle, an inclined runway for receiving balls emitted from said receptacle and to return the same to a player's 25 stand, and an incline disposed beneath said runway to return balls, which fail to enter 30 said receptacle, to said player's stand.
4. A game of the class described, comprising stationary missile receiving receptacle, upper and lower runways disposed beneath said receptacle and adapted to return missiles 35 thrown toward said receptacle to one side of the game, said runways terminating adjacent to a ball receiving table, and means for elevating the balls carried by the lower runway to a position in substantial alinement to 40 the plane of said table, whereby said balls may be deposited upon the table.
5. A game of the class described, comprising a target of receptacle formation, upper and lower runways coöperating with said receptacle and utilized to return missiles thrown into and to one side of said receptacle to a player's position, means for retaining balls in the lowermost portions of said runways, and manually operated mechanism 45 for moving said means, whereby said balls may be deposited upon a common ball receiving table.

In testimony whereof I affix my signature.

KATE A. BRADLEY.
